WRITING INSTRUMENT OR THE LIKE

Parker Z. Bloser, Columbus, Ohio, assignor to The Zaner-Bloser Company, Columbus, Ohio, a corporation of Ohio

Original application September 14, 1954, Serial No. D. 32,271, now Design Patent No. 178,632, dated September 4, 1956. Divided and this application June 25, 1956, Serial No. 42,020

Term of patent 14 years

(Cl. D74—17)

Fig. 1 is a perspective view of a writing instrument showing my new design;

Fig. 2 is a cross sectional view thereof taken on line 2—2 of Fig. 1;

Fig. 3 is a top plan view of the uppermost tip portion; and

Fig. 4 is a cross sectional view taken on line 4—4 of Fig. 1.

The essential features of my design reside in the portions shown in solid lines on the drawing.

This is a division of my application Serial No. D. 32,271 filed on September 14, 1954 and now Patent No. D. 178,-632 granted September 4, 1956.

I claim;

The ornamental design for a writing instrument or the like, substantially as shown and described.
